UNITED STATES PATENT OFFICE.

JACOB SCHAUB, OF GREENDALE, INDIANA, ASSIGNOR TO THE THEROZ COMPANY, OF NEW YORK, N. Y., A CORPORATION OF DELAWARE.

CAPSULE.

Application filed January 18, 1921. Serial No. 438,175.

To all whom it may concern:

Be it known that I, JACOB SCHAUB, a citizen of the United States, residing at Greendale, in the county of Dearborn and State of Indiana, have invented certain new and useful Improvements in Capsules, of which the following is a specification.

My invention relates to an improvement in capsules.

10 Hitherto gelatinous capsules have been employed in the general form of a bird's-egg in design, to contain liquid such as butter color for example, although obviously they might be employed as a container for any other liquid, such as medicine or the like. The foregoing type of container has generally been made of two moulded parts, which are joined together and sealed at their edges.

20 In using these capsules for butter color and the like, it has been the custom to prick a hole in the capsule, and then squeeze out the contents; but the objection has been that no definite direction could be given to the contents as it squirted from the capsule, and 25 it was as liable to go in one direction as another, and perhaps in the face, the eyes, or on the clothing of the person using the capsule.

The present invention is designed to ob-30 viate the foregoing objection as well as to provide a capsule which can be easily and quickly made, filled and sealed by machinery in a continuous operation, and in the method of making the same.

35 My present invention, therefore, may consist in a tubular capsule cut and sealed on two bias edges, thereby giving it the form of a diamond, trapezoid, or parallelogram, thus presenting two or more sharp or acute 40 angular points at its opposite ends, either of which may be pinched or cut off, and the contents squeezed out and given definite direction as it leaves the capsule, thereby insuring against the contents being discharged 45 without being given controlled direction.

My invention consists in a seamless gelatinous capsule of the general form of a diamond, trapezoid, or parallelogram, or of a shape to have at least one sharp or acute angle, even if not diamond-shape.

In the accompanying drawings:

Fig. 1 is a plan view;

Fig. 2 is a side elevation;

Fig. 3 is a view of the tube from which 55 the capsule is formed;

Fig. 4 is a view showing the same collapsed;

Fig. 5, is a section on line 5—5 of Fig. 1;

Fig. 6 shows the capsule in trapezoid form; 60

Fig. 7, in the form of a parallelogram.

A, represents my improved capsule. This is preferably made from a tube of gelatinous material filled with any desired liquid, preferably in the process of making the same, 65 and cut from the main tube upon a bias or diagonally, and sealed at the cut edges 1 and 2 by being pinched together while in a plastic condition.

In the preferred form, these cut edges are 70 parallel, thus imparting to the capsule the general form of a diamond, trapezoid, or parallelogram.

But in one of the modified forms, the cut ends might be at an angle to each other, as 75 shown in Fig. 6, thus having the same effect of forming at least one, if not two, sharp or acute angular, cone-shaped discharging ends 3.

Obviously the capsule might be in still 80 other forms, for example each alternate cut might be transverse or at right-angles, as shown in Fig. 7, although for obvious reasons it is now considered that the diamond, or trapezoid or parallelogram shape would 85 be preferable, for the reason that it is probably easier to make it in this form, and the contents can be discharged with greater certainty of direction and convenience when 90 used.

The contents may also be discharged in a definite direction without diffusion and without squeezing of the capsule by merely cutting or pinching off the two sharp points, and permitting the liquid content to flow 95 gently by gravity from the capsule while holding the capsule in an upright position.

The size might, of course, be varied to suit requirements, but it is the intention to make the capsule contain just the required amount 100 of coloring or other liquid content.

A capsule of any of these forms is easily made, and it is most effectual in facilitating the use of the material contained within, as it is easy to manipulate, to open and to empty, and insures against the contents discharging in any direction other than that intended.

Furthermore, the general shape gives 110 character to the capsule, and makes it easy

to distinguish from others, and more of them can be packed and stored in a given space when in this form than when the capsules are of egg-shape.

5 It is understood that the sharp and acute end or ends are conical in cross-section, as shown in Fig. 5, when the capsule is filled, thus facilitating and insuring the directing of the contents out through the sharp point 10 of the capsule, when punctured or opened.

I claim:

1. A gelatinous capsule formed of a tube

having the ends thereof transversely cut at an angle and pinched together while in a plastic condition to close said ends.

16

2. A gelatinous capsule formed of a seamless tube having the ends thereof transversely cut at an angle to the axis of said tube and pinched together while in a plastic condition to close said ends and forming angular corners for the discharge of the contents.

20

In testimony whereof I affix my signature.

JACOB SCHAUER.
